DUAL CONTROL SWITCH

Frederick G. Beuer, St. Louis, Mo., assignor to
 Carter Carburetor Corporation, St. Louis, Mo.,
 a corporation of Delaware

Application August 23, 1948, Serial No. 45,621

2 Claims. (Cl. 200—153)

1

This invention relates to switch devices and consists in an improvement on the transmission kick-down switch device illustrated in Boyce Patent No. 2,396,551.

In the above patent, the switch which controls the so-called kick-down device associated with the automobile transmission, consists of a stationary and a movable contact and an actuator for the movable contact which operates with the throttle valve to close the switch contact. A cylinder exposed to engine suction intersects the contact and a piston operates in the cylinder and carries a resilient finger which is interposed between the contacts, when the suction applied to the cylinder is below a predetermined value, so as to permit closing of the switch contact. At periods of higher suction, the piston is lifted, removing the spring finger from between the contacts and preventing their closure thereafter.

In this arrangement, the piston is formed of Bakelite and the spring finger comprises a very small angular spring piece which is attached to the bottom of the piston by a screw. This operation is difficult because of the very small parts involved and, particularly, the tapping of the piston for the spring finger attaching screw is a difficult operation.

The main object of the present invention is to simplify the construction and assembly of the spring finger arrangement in the above type of switch.

This object and other more detailed objects hereafter appearing are attained by the device illustrated in the accompanying drawing in which

Fig. 1 is a diagrammatic representation showing part of an automotive engine and controls therefor.

Fig. 2 is a side view of a portion of the carburetor enlarged, and showing the switch in vertical section.

Fig. 3 is a detail elevation of the piston removed from the assembly.

Fig. 4 is a vertical transverse section through the piston, taken on line 4—4 of Fig. 6.

Fig. 5 is an elevation of the piston on the other side of that shown in Fig. 3.

Figs. 6 and 7 are cross sections of the piston taken on the corresponding section lines of Fig. 4 and showing the spring clip in position.

Figs. 8, 9 and 10, are side, rear, and bottom views, respectively, of the spring clip disassembled.

Fig. 1 shows an automotive engine 12 having an intake manifold 13 and carburetor 14. Rearwardly of the engine there is provided the clutch in

2

housing 15 and transmission 16 provided with a rearward extension 17. The carburetor is provided with the usual throttle valve 18 which is operated from the driver's compartment by linkage 19 and pedal 20. A gear shift lever is shown at 21. A kick-down control solenoid 22 mounted on portion 17 of the transmission is connected by suitable wiring to storage battery 23 and a switch, generally indicated at 24, mounted on the carburetor.

The switch, to which this invention particularly pertains, has an angulate body 27 cast integral with the carburetor body and hollow to form intersecting cylinders 28, 29 and 30. A stationary 15 switch contact 31 is mounted in the switch body at the intersection of cylinders 28 and 29. A movable switch contact plunger 32 is slidably received in cylinder 29 and has a telescoping portion 33 projecting outwardly thereof through 20 cover plate 35. Plunger 32 is maintained in its rightward position by a coiled spring 35 and projecting plunger 33 is maintained extended by a coiled spring 36 therein.

An arm 37 rigid with the throttle valve has an 25 extension 38 which is disposed to engage telescoping plunger 36 as the throttle valve is fully 30 opened so as to urge movable contact plunger 32 leftwardly to close the switch contacts. Telescoping portion 33 of the plunger permits overrunning of the throttle without damaging the parts.

A piston 40 works in cylinder 28 and its upper 35 surface is exposed to engine produced suction within the carburetor by means of a passage 41. The piston is constantly urged downwardly by a 40 coiled spring 42. The intermediate portion of the piston is provided with a longitudinal slot 43 which, as best shown in Fig. 5, is of keyhole shape. The lower portion of the slot embraces contacts 31 and 32 so that the piston may slide longitudinally 45 in its cylinder with its movements limited only by the top and bottom walls of the cylinder. The body of the piston is formed conveniently of a piece of cylindrical stock of plastic material with its upper portion hollowed, as at 44, to accommodate spring 42. A pair of cuts 45 in one face of the piston body at the upper end of slot 43 (Figs. 3 and 7), leaves a tongue 46 forming a transverse wall 47 across the upper portion of the slot. The cuts 45 are of sufficient depth to expose 50 recesses, as at 48, at each side of tongue 46. As best shown in Figs. 4, 5 and 6, the widened upper portion of the slot is bounded at one end by the transverse wall 47 formed by finger 46. A pair of 55 opposing lugs 50 are formed in the upper corners of the slot adjacent transverse wall 47.

Received in this keyhole-shaped slot is the spring clip element shown disassembled in Figs. 8-10, inclusive. This element has a generally U-shaped body 52 formed of a spring strip and with a depending finger portion 53. The legs of strip 52 have outwardly projecting ears 54 on their edges adjacent strip 53.

To assemble the piston and spring clip, the legs of the U-shaped strip are compressed so that the element will enter the side of the keyhole slot shown in Fig. 5. When the clip is fully inserted, the cross bar and upper leg portions thereof abut lugs 50, as shown in Fig. 6, and ears 54 slip behind the shoulders formed by recesses 48 (Fig. 7). The engagement at these points locks the spring clip element against transverse movement. Longitudinal displacement of the clip element is prevented by the close fit of the enlarged upper portion of the U-shaped spring clip within the correspondingly shaped portion of the slot in the piston.

The clip is thus firmly lodged in such position so that finger 53, normally, is interposed between contacts 31 and 32. Under this condition, actuation of movable contact 32 by actuator 38, will cause closure of the switch. Increase of the suction applied to the upper surface of the piston, withdraws spring finger 53 upwardly after which, because of limited movement of plunger 32, the switch points cannot close.

Depending cylinder 30 is formed on the under side of cylinder 29 and receives a piston 61 constantly urged upwardly by a coil spring 62. A detent finger 63, on the upper surface of this piston, serves as a latch in cooperation with telescoping plunger 33 under certain suction conditions. This feature is more fully described and claimed in a co-pending application, Serial No. 28,897, filed May 24, 1948 in the name of Leonard D. Boyce.

This invention may be modified as will occur to those skilled in the art without departing from the spirit thereof and the exclusive use of

all modifications as come within the scope of the appended claims is contemplated.

I claim:

1. A switch device comprising a pair of contacts, at least one being movable, an actuator for said movable contact, a guide member movable in a line intersecting said contacts and having a longitudinal keyhole shaped slot with opposed recesses in the sides thereof, and a keyhole shaped, laterally resilient element lodged in said slot and having lateral ears seated in said recesses for firmly securing said element to said guide member, said element also having a central tongue movable to and from positions between said contacts for affecting the operation thereof.
2. A switch device comprising a pair of contacts, at least one being movable, an actuator for said movable contact, a member having a slot straddling said contacts and movable transversely thereof, there being a transverse wall and adjacent opposed shoulders in said slot, and a spring clip element lodged in said slot with edges abutting said wall and ears resiliently seated behind said shoulders to maintain the assembly, said element also having a centrally projecting finger interposable between said contacts to affect the closure thereof by said actuator, said slot and said spring clip element being of keyhole shape for resisting longitudinal displacement of said element.

FREDERICK G. BEUER.
